UNITED STATES PATENT OFFICE.

JOHN W. HENDERSON, OF PHILADELPHIA, PENNSYLVANIA.

RAILWAY-SIGNAL.

SPECIFICATION forming part of Letters Patent No. 331,879, dated December 8, 1885.

Application filed January 2, 1884. Serial No. 116,200. (No model.)

To all whom it may concern:

Be it known that I, JOHN W. HENDERSON, of the city of Philadelphia, county of Philadelphia, and State of Pennsylvania, have invented an Improvement in Railway-Signals, 5 of which the following is a specification.

My invention has reference to railway signals and switches; and it consists in certain mechanism by which the signals or switch at 10 one or more points may be operated positively, with a cable terminating in the switch-station, which may be very distant from the said signals or switches, the said cable being so constructed and combined with suitable mechanism that it acts positively, like a rod or tube; 15 further, in so forming the signal apparatus that should the actuating-cable become broken the danger-signal will be automatically displayed and the operator will be notified of 20 such derangement or breakage, and in details of construction, all of which are fully set forth in the following specification and shown in the accompanying drawings, which form part thereof.

25 The object of this invention is to provide railroad signals or switches with safety or detecting attachments by which any defect in their working is at once apparent; also, to work a signal or switch of this class with cables as effectively and positively as when rods or tubes are used to work said signals or switches from 30 distant points, thereby greatly reducing the cost of construction; also, to so construct the signal that should its operating-cable become 35 broken the danger-signal will be automatically displayed.

In the drawings, Figure 1 is an elevation showing my improved railway-signal; Fig. 2, an elevation of the upper part of the signal-post and its arm, and shows its connections with the electrical detector. Fig. 3 is a plan view of the cam-plate for directly operating the signal-arm, and shows its connection with the actuating-levers and the switch. Fig. 4 40 is a sectional elevation of the electrical detector or indicator. Fig. 5 is an elevation of a modified form of signal-actuating cam. Fig. 6 is an elevation of a modified arrangement of the intermediate connections for the cables. 45 Figs. 7 and 8 are modified forms of construction of electrical indicator or detector. 50

A is the block-station, or switch and signal operator's house.

B is the signal-lever, which works on a segment, B², and may be secured in its two extreme positions by a bolt, b, which enters slots or notches in said segment in the usual manner. The lever B is made T-shaped, to one leg of which is secured a very heavy weight, B', (say twelve hundred pounds,) and to the other arm of which is hinged the bar C', whose lower end is pivoted to one arm of the bell-crank C, the other arm of which crank is connected with the end of the cable D. The other end, d², of the cable passes over a pulley, G, 65 and is secured to a weight, G', of less weight than B', but heavier than could be pulled at B by a man if B' were removed, (say eight hundred pounds.) This cable D is cut preferably at the middle, and the ends d d' are secured 70 to opposite sides of the same wheel, E, so that if said wheel is turned it will pay out or draw in on both of said sections of cable.

Secured to wheel E is a wheel, E', around which is a cord, F, to the end of which is a 75 heavy weight, F', (say two thousand pounds,) and this cord F is so arranged that it tends to turn the wheel E, so as to wind in said cable-sections and put them under great tension. Now, as the weight F' practically counterbalances the weights B' and G', the only force to be overcome in operating the signal is the friction produced by the cable and its connections.

Considering the device so far, it is evident 85 that as the cable D over its entire length is put under such great tension its effect is as positive as if composed of a stiff rod, bar, or tube. If the cable D is cut nearer one end than the other, the ends d and d' would be 90 secured to pulleys or drums of proper diameters, so that they shall allow for all expansion or contraction in said sections—that is, the longer the section the larger the diameter of the drum to which it is secured, and 95 these drums would make up the drum E, as they would be secured together side by side.

In the drawings the cable D is supposed to be cut in the middle; hence the drums E would be of equal diameters, or one drum is used, as 100 shown.

Interposed in the cable close to the wheel

G is the cam device H for operating the signal, which consists of the cam-plate H', which is guided in supports I, and provided with a slot having two straight parts, h h, in line, 5 and connected by the converging oblique parts h' h' with the straight parts h², which are made parallel with parts h.

J J' is the signal crank or lever, the arm J of which is provided with a pin or roller 10 which works in the slot in said cam-plate, and the arms J' of which are connected with the signal device proper.

L is the signal-post carrying at the top the lamp N and pivoted signal-arm M, which is pivoted at m, and provided with the red glass bull's-eye M', to warn "danger" in the night-time. This pivoted arm M is actuated by rod k, which is reciprocated by a bell-crank, K' and which bell-crank is operated by a rod or 20 bar, K, connecting with one arm, J', of the crank J J'. If two signals are to be used on the same post L, one is raised when the other is lowered. The second of said signal-arms may be worked from the other arm, J', of 25 said crank. (See Fig. 3.) As shown in Figs. 1 and 3, the signal-arm M is lowered, and to raise it to the position shown in Fig. 2 the lever B is shifted. This allows the weight F' to come into play, winding the end d' of 30 cable D upon the wheel E, raising weight G' and moving the cam-plate H' to the left. This action rocks lever J J' and raises the arm M as desired. Now, should the cable D between wheel E and bell-crank C break 35 when the arm M is lowered, it is evident that the preponderance of the weight F' over weight G' will shift the cam-plate H', as before, raising the said arm. Now, should the cable D break between the wheel E and cam-plate 40 H', then the power of the weight G' shifts the plate to the right, and the other end of the slot comes into play to raise the signal-arm. If the cable should expand or contract lengthwise, the increase or decrease is taken up or 45 given out by wheel E rotating automatically, if it be located at or about the center of said cable, and the expansion and contraction is uniform in both sections; but should either the section to the left of wheel E or to the 50 right of it expand or contract separately, then the straight parts h h² of the slot in cam-plate H allow for such expansion, and thereby overcome any danger of raising the arm M partly away, as often happens in signals as now generally constructed. If desired, the railroad-switch P may be operated directly by said cam-plate H', through the agency of a rod, O, which is actuated by the slot in said plate H', as shown in Fig. 2. By this construction, 55 when the switch is open for the siding, the danger-signal is displayed. The switch can be worked by a separate cable and cam-plate, the plate being so arranged that a breakage of the cable will cause the switch to be set for 60 the main line.

In place of the connections for the divided cable D, (shown in Fig. 1,) that shown in Fig.

6 may be used, it being similar to that already described, except that the end d' is connected to the wheel E², used before as an idler-wheel 7c to bring the two sections of cable into line, and the cord F is passed around said wheel E² (preferably one or two times) as well as E'.

In place of using wheels, levers may be used, as indicated in dotted lines, and in lieu of 75 weight F' a spring, F², might be substituted.

In place of the cam mechanism H, (shown in Figs. 1 and 3,) that shown in Fig. 5 may be used. In this case the cam-plate H' is pivoted and the straight parts h h² of the slot are made 80 curved and concentric with the pivotal point of the said plate or disk H'. A lever, K', similar to that described, may be used, or simply a straight one, as shown, which is connected directly with the bottom of rod k. The 85 cable D then passes around a pulley secured to the back of said disk, and may be pinned thereto. In the position shown the signal-arm would be down and the roller of the lever K' would be in the concentric part h² of the cam-slot of disk H', and would allow of expansion and contraction of the cable D without moving 90 said lever. If, now, it be desired to raise the signal-arm, the lever B is moved and the cable D is slackened, the weight G' taking up 95 the slack cord and rotating the disk H', causing the part h' of the cam-slot to move the lever K', and finally the concentric part h of the cam-slot is brought into action on the roller of lever K', and allows for expansion and contraction of 100 cable D when the signal-arm is raised. This will prevent any undue movement to the signal-arm when down or up, preventing erroneous or uncertain signals. The slot h h' h² is made double, so that if the disk H' rotates in either 105 direction the same action will take place. If the cable should break, the disk would be rotated and display the danger-signal. The arm M, when brought to its two extreme positions, 110 comes in contact with contact-springs R R', connected by wires r r' with an indicator, S, in the operator's house A. The pivot m of the arm M is also connected with said indicator S by a wire, r², and has a battery, R², located therein. If desired, this line r² may be made 115 a ground-wire.

The indicator may be constructed as follows: Referring to Fig. 4, the wires r r' are in circuit with magnets S³ S', between the poles of which is an armature, S², connected with a 120 pivoted hand or pointer, S', which, when in the position shown in said figure, indicates that the arm M is neither up nor down and the signal is either in a state of transition or working defectively; but when attracted by 125 electro-magnet S³ indicates that the arm is down, and when attracted by electro-magnet S⁴ indicates that it is up. The wires r r' are also in circuit with electro-magnets T T', and are then connected together and unite with the 130 wire r². The armatures T² of the electro-magnets T T' are pressed against contact-screws T³ by springs t when no current passes, and this closes a local circuit by wire U through

battery U' and alarm U^2 . If desired, the battery U' may be dispensed with and the circuit U derive its current from battery R^3 . When the arm M is up, as shown in Fig. 2, the circuit is closed through wire r and electro-magnets S^4 and T^4 , the former of which attracts the armature S^2 , causing the needle or pointer S' to point to red (see Fig. 2) and the latter to break the local circuit U by attracting its armature T^2 . When the arm M is down, the same effect is produced, but by magnets S^3 and T , and the pointer S' points to white. In the act of raising or lowering the arm the alarm U^2 should ring. If it does not, the device is out of order.

In place of the construction of indicator shown in Fig. 4, that shown in Fig. 7 may be used, in which the magnets $T T'$ are dispensed with and spring-contacts $t' t'$ used for the local circuit U ; or that shown in Fig. 8 may be used, in which the magnets $T T'$ are also dispensed with, but the armatures T^2 worked by the magnets $S^3 S^4$. The detector is also as applicable to switches as to signals.

Any other form of indicator may be used and utilized to indicate the position of a switch as well as the signal, or the cam mechanism may be varied, as I do not limit myself to the details of construction.

I am aware of the British Patent No. 1,079 of 1880, and do not claim anything thereon shown or set forth.

Having now described my invention, what I claim as new, and desire to secure by Letters Patent, is—

1. A railroad signal provided with an actuating-cable, mechanism to keep said cable under tension, and take-up devices to compensate for uniform expansion or contraction of said cable, in combination with a switch and connecting mechanism, whereby the same cable which actuates the signal also actuates the switch, substantially as and for the purpose specified.

2. A railroad signal or switch provided with an actuating-cable and mechanism to keep said cable under tension, whereby it is operated for long distances with all the effects, and the power to be exerted by the operator shall be practically only sufficient to overcome the friction of a rigid rod or tube, and cam mechanism to automatically cause the signal-arm to be thrown up to indicate the danger and close the switch should said cable break, in combination with detecting apparatus to indicate whether the arm of said signal or switch is in its extreme positions or in an intermediate position, substantially as and for the purpose specified.

3. The combination of lever B and its weight B' , cable D , wheels $E E'$, rope or chain F , weight F' , pulley G , and weight G' , with a signal device and switch actuated by said cable, and a detecting device to indicate the position of the signal arm or switch, substantially as and for the purpose specified.

4. The combination of lever B and its weight B' , cable D , wheels $E E'$, rope or chain F ,

weight F' , pulley G , and weight G' , with cam-plate H' , having slots $h h' h^2$, lever K' , and a danger-signal actuated by said lever, substantially as and for the purpose specified.

5. The combination of pivoted cam-plate H' , having slots $h h' h^2$, with a switch or signal, substantially as and for the purpose specified.

6. In a railroad signal or switch, an actuating-cable, in combination with weights at each end to keep said cable under tension, an automatic weighted take-up device arranged to act upon said cable at a point between its ends, an operating-lever to act upon the cable between two adjacent weights, a switch or signal arranged to be operated by said cable at a point between the other end and middle weight, whereby said cable is operated with all the effect of a rigid rod, and devices, consisting of wheels $E E' E^2$, cable F , and weight F' , to allow for differential expansion or contraction in said cable without operating the said switch or signal, substantially as and for the purpose specified.

7. In a railroad signal or switch, a cable formed in two parts, in combination with mechanism to draw said parts together, weights or their equivalent to act upon the extreme ends to draw said parts asunder, and a slotted cam-plate having slots $h h' h^2$, adapted to actuate said switch or signal attached to and operated by said cable, substantially as and for the purpose specified.

8. In a railroad switch and signal, the combination of a cable, weights at each end to keep said cable under great tension, a weighted take-up device, substantially as described, arranged to act upon said cable at a point between its ends to compensate for expansion and contraction, a switch and a signal, connecting levers and bars to actuate said switch and signal, and cam mechanism consisting of cam-plate H' , having slots h, h' , and h^2 , operated by said cable to actuate both the signal and switch simultaneously, substantially as and for the purpose specified.

9. In a switch and signal, the combination of a cable heavily weighted at each end, so as to be operated with all the effect of a rigid bar, and cam mechanism consisting of cam-plate H' , having slots $h h' h^2$, actuated by said cable to simultaneously operate both the signal and switch, a switch and signal, and connecting levers, rods, and bars by which said slots in the cam-plate actuate said switch and signal, substantially as and for the purpose specified.

10. A railroad signal or switch provided with an actuating-cable and end weights to keep said cable under tension, whereby it is operated for long distances with all the effects, and the power to be exerted by the operator shall be practically only sufficient to overcome the friction of the rod or tube, a hand-lever to operate said cable, and a cam-plate operated by said cable to actuate said switch or signal, in combination with a detecting apparatus to indicate whether the arm of said sig-

nal or switch is in its extreme positions or in an intermediate position, substantially as and for the purpose specified.

11. A railroad-signal provided with an actuating cable and mechanism to keep said cable under tension, whereby it is operated for long distances with all the effects, and the power to be exerted by the operator shall be practically only sufficient to overcome the friction of a rigid rod or tube, cam-plate H', having slots h h' h^2 , and connecting mechanism, the whole being operated to automatically cause the signal-arm to be thrown up to indicate danger the instant the actuating-lever is freed, should cable break beyond the signal,

substantially as and for the purpose specified.

12. The combination of lever B and its weight B' with cable D, wheels E E', rope or chain F, weight F', pulley G, weight G', cam-plate H', having slots h h' h^2 , a switch or signal, or both, and connecting mechanism, the whole being constructed and operated as and for the purpose set forth. 20

In testimony of which invention I hereunto set my hand.

JOHN W. HENDERSON.
